AGITATOR

Peter Eduard Geldhof, St. Joseph, Mich., assignor, by
mesne assignments, to Whirlpool-Seeger Corporation,
St. Joseph, Mich., a corporation of Delaware

Application November 8, 1950, Serial No. 194,714

2 Claims. (Cl. 68—133)

This invention relates to new and useful improvements in apparatus for washing clothes and the like, and more particularly relates to a clothes washing machine and agitator arranged with a view toward increasing the efficiency of the clothes washing operation.

A principal object of my invention is to provide a novel and improved form of agitator particularly arranged to more efficiently carry out the clothes washing operation than formerly.

Another object of my invention is to provide a new and improved form of agitator for clothes washing machines having the combined advantages of both the spiral and vane types of agitators heretofore used.

A still further object of my invention is to provide a new and improved form of agitator for clothes washing machines having a spiral vane at the upper part of the agitator, terminating into a radial vane adjacent the lower end thereof.

A still further and more detailed object of my invention is to provide a novel form of agitator for clothes washing machines wherein a plurality of agitating vanes extend in spiral paths downwardly along the face of an upstanding cone of a concave formation and extend radially in planes normal to the face of the cone, adjacent the lower end thereof.

These and other objects of my invention will appear from time to time as the following specification proceeds and with reference to the accompanying drawing wherein:

Figure 1 is a fragmentary view in side elevation of a washing machine and tub, with certain parts thereof broken away and in section, and showing an agitator constructed in accordance with my invention mounted in the tub;

Figure 2 is a top plan view of the agitator shown in Figure 1;

Figure 3 is a sectional view taken substantially along line III—III of Figure 1;

Figure 4 is a sectional view taken substantially along the line IV—IV of Figure 1; and

Figure 5 is a fragmentary sectional view taken substantially along line V—V of Figure 1.

In the embodiment of my invention illustrated in the drawing, an agitator 10 is shown as being mounted in a clothes container or tub 11, of a clothes washing machine designated generally by reference character 12. The tub 11 may be of any well known form having an open central portion with a hollow center post 13 extending upwardly therefrom upon which the agitator 10 may be oscillatively mounted as is well known to those skilled in the art, so not herein shown or described in detail. A vertical shaft 14 extending upwardly through the center post 13 may serve as a drive means for the agitator and may be oscillatively driven from the motor (not shown) of the washing machine 12 through oscillatable drive gearing generally indicated by reference character 15, of a well known construction, so not herein shown or described in detail.

The agitator 10 may be hollow and the hollow central

2

upper end portion thereof is herein shown as being hexagonal in horizontal section, to afford a means for driving said agitator from a corresponding upper end portion of the shaft 14. A hand screw or nut 17, may be threaded on the shaft 14 into engagement with the top face of the agitator 10 to retain said agitator to said shaft.

The agitator 10, as herein shown, has a generally conical outer wall 18 concave in transverse cross-section and converging from a relatively wide base to a generally cylindrical wall at its upper end. A plurality of agitating vanes 19—19, herein shown as being three in number, are spaced equally around the conical wall 18, and diverge laterally from said wall from the top thereof, and spiral down said wall to a position adjacent the base thereof, from whence they change their spiral configuration and extend in a radial direction to the lower edge of said wall in the form of radial upright vanes extending in planes normal to the surfaces of the cone. A plurality of rubbing projections or vanes 20, 20 extend radially of the lower portion of the wall, intermediate the vanes 19, 19 to subject the clothes drawn thereacross by the vanes 19, 19 to a slight rubbing action and to aid in the loosening of the dirt in the clothes.

As shown in Figures 1 and 2 of the drawing, the vanes 19 are spaced substantially 120° apart, at their starting point, adjacent the top of the conical wall 18, and diverge therefrom as they traverse downwardly therealong gradually increasing in height, and terminate substantially 180° from their starting point. The vanes 19 adjacent their upper ends are shown as starting from the generally cylindrical upper wall portion of the cone in a direction substantially normal to the surface of said wall, and diverge angularly with respect thereto at a slightly negative rake as they initially extend downwardly therealong, when the agitator is turning in a clockwise direction, the angle of divergence being indicated by reference character A in Figure 3. The rake of each vane may approach an angle normal to the surface of the cone at a point intermediate the ends thereof, and said vanes may then pitch in an opposite direction to a slightly positive rake upon a clockwise rotation of the agitator the angle of divergence being indicated by reference character B in Figure 4. The positive rake for clockwise rotation of the agitator may gradually increase to a predetermined point and the angle of rake of the vanes may then gradually change to extend at an angle normal to the surface of the conical wall 18 downwardly to the edge of the base of the cone in radial directions in the form of radial vanes as shown in Figure 5.

The vanes 19 thus have a uniform spiral configuration with respect to the surface of the conical wall 18, and have rakes in one direction at the upper part of the cone and rakes in an opposite direction at an intermediate portion of the cone which blend into radial vanes at the lower part of the cone extending at substantially 180° to the upper starting edges of the vanes.

Upon rotation of the agitator in a clockwise direction, the clothes are circulated outwardly by the flow of washing fluid created by the radial lower portions of the agitator vanes, and the clothes and washing fluid in the tub tend to pass by the upper spiral edges of the vanes 19 which draw the washing fluid downwardly along the agitator, moving the clothes in a circular path from and toward the agitator as they advance around the tub.

Upon reversal of oscillating movement of the agitator, the radial edges of the vanes will create a reverse propelling effect and the positive rakes of the upper edges of the vanes will create a similar downward flow of water along the agitator, propelling the clothes downwardly therealong advancing the clothes around the tub in an opposite direction. Upon again reversing the direction of movement of the agitator, a new batch of clothes is

propelled outwardly around the tub by each agitator vane, and progressed to the top and downwardly along the agitator in a clockwise direction. Since, however, the rakes of the upper parts of the vanes are in negative directions and the rakes of the lower parts of the vanes are in predominantly positive directions, when the agitator is oscillating in a clockwise direction, and converge into planes normal to the wall 18 at the lower wall portion of the cone, the tendency to propel the clothes around the tub will be greater when the agitator is moving in a 10 clockwise direction than in a counterclockwise direction.

More of the clothes, therefore, will slip by the agitator when moving in a counterclockwise than a clockwise direction. The result will be that the clothes will positively circulate around the tub in a clockwise direction as they rotate from the bottom of the tub to the outside of the tub and then rise to the top of the tub and are then drawn downwardly by the circulation created by the spiral vanes of the agitator. This will rotatably move the clothes within the tub in vertical planes as they travel around the tub in a clockwise direction, progressing the clothes around the tub in a spiral path about a horizontal axis extending in an annular path within the limits of the tub.

It will be understood that modifications and variations may be effected without departing from the scope of the 25 novel concept of the present invention.

I claim as my invention:

1. In a clothes washing machine, a tub for clothes and washing fluid, a clothes washing agitator mounted in said tub for oscillatable movement about a vertical axis, means 30 oscillatably driving said agitator, said agitator having an upstanding generally conical outer wall concave in cross section and converging in a uniform curve from a relatively wide circular base to a relatively small diameter cylindrical column adjacent the upper end of said agitator, and having a plurality of equally spaced agitator 35 vanes diverging from said column at their upper ends and extending downwardly therealong in spiral path from the upper end of said column along said conical outer wall, for a greater portion of the length thereof, and increasing 40 in height from the upper to the lower end of said column and extending normally to the surface of said cone in

5

straight line paths for the balance of the length thereof, toward the base of said cone, and a radial rubbing vane projecting from the lower surface of said cone intermediate the normal projecting portions of each of said vanes.

2. In an oscillatable agitator for washing clothes in a tub, a hollow cone adapted to be supported and oscillatably driven from the interior thereof and having a relatively large diameter circular base having a concave conical outer wall extending upwardly from said base in a uniform curve and converging therefrom to a small diameter cylindrical column at the upper end thereof, and a plurality of equally spaced agitator vanes extending downwardly along said wall from the upper end thereof and diverging from said wall as they extend downwardly therealong, said vanes extending in spiral paths for greater portions of their length and terminating in radial vanes at the base of said cone within the peripheral limits of said base and increasing in height from the upper to the lower ends thereof, said radial vanes extending along said cone in diametrically opposed relation with respect to the upper ends thereof, and a radial rubbing projection extending from the surface of said cone along the base portion thereof intermediate each pair of said radial vanes.
